(57) CLAIM

The ornamental design for a multifunctional fitness board as shown and described.

DESCRIPTION

FIG. 1 is a top perspective view of a multifunctional fitness board showing my new design;

FIG. 2 is a bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a bottom plan view thereof;

FIG. 8 is a top plan view thereof; and,

FIG. 9 is a top perspective view thereof, showing the multifunctional fitness board in a folded configuration.

The broken line showing of a multifunctional fitness board is included for the purpose of illustrating portions of the article and forms no part of the claimed design.

1 Claim, 9 Drawing Sheets
